UNITED STATES PATENT OFFICE.

RICHARD SAVAGE, OF CHICAGO, ILLINOIS.

APPARATUS FOR OPERATING CONFECTIONERY-KETTLES.

SPECIFICATION forming part of Letters Patent No. 499,890, dated June 20, 1893.

Application filed February 13, 1892. Serial No. 421,470. (No model.)

To all whom it may concern:

Be it known that I, RICHARD SAVAGE, of Chicago, Illinois, have invented certain new and useful Improvements in Apparatus for Operating Mixing-Kettles, of which the following is a specification.

My invention relates to improvements in means for operating mixing kettles, in which a kettle is supported and tilted in conjunction with mechanism for operating a stirrer therein; and one of the objects of my improvements is to provide operating mechanism, supported in conjunction with the kettle, for operating the stirrer, which is adapted 15 to work the stirrer when the kettle is in its normal or upright position, and not interfere with the tilting of the kettle for emptying and cleaning.

Another object is to provide means where- 20 by the stirrer may be readily detached from the operating mechanism, so that it may be removed from the kettle.

A further object is to provide means for holding the kettle in different positions between the vertical or normal position and the extreme point of inclination.

A still further object is to provide means for circulating steam under the kettle so as not to disconnect the circulation by the tilting of the kettle, and means for drawing off the condensation.

These objects I attain by the mechanism illustrated in the accompanying drawings, in which—

35 Figure 1 is a side elevation of an apparatus containing my invention, showing the kettle partially tilted. Fig. 2 is a side elevation of the kettle detached and viewed at right angles to the view seen in Fig. 1. Fig. 3 is an enlarged vertical central section through the entire apparatus. Fig. 4 is a horizontal section on the line 4—4 of Fig. 3, and shows the plan of the apparatus. Fig. 5 is an enlarged detail showing a vertical section on the line 5—5 of Fig. 4. Fig. 6 is an enlarged detail showing in plan view, a fragment of one of the stirring devices, with one of the scrapers attached thereto.

In the drawings, A designates a standard 50 for supporting a suitable frame A', which consists preferably of a semicircular piece secured to the standard and provided with suit-

able bearings, a in which the trunnions, a' of the kettle B may rest and revolve, there being a suitable brace rod connection, as shown 55 in Fig. 1, for connecting said frame with the floor to hold it securely in place. On the frame, there is mounted a shaft, A², in a suitable bearing, and provided at one end with a friction clutch, A³, by which it is connected 60 with, and disconnected from an operating pulley, A⁴, by means of a screw, a², operated by a lever, a³, which is adapted when thrown in one direction, to move the clutch A³ into connection with pulley, A⁴ and when thrown 65 in the opposite direction, to disconnect said parts.

To the top of the kettle and at one side, I connect a supplemental frame B' on which is mounted in suitable bearings, a shaft B². On 70 the outer end of this shaft, B² I attach a gear wheel, B³ which gears into a pinion, b on the inner end of shaft A² when the kettle is in its upright or normal position; and on the inner end of said shaft B² is placed a gear c² 75 for operating a stirrer or stirrers supported on the inner end of said supplemental frame B'. In the present instance, I provide two stirrers and adapt them to revolve in opposite directions. One of said stirrers consists 80 of two arms C attached to a shaft, C' which is stepped or journaled on the bottom of the kettle, passes through a sleeve, C² and is provided with a miter gear, c near the top. The other of said stirrers consists of a loop or 85 hoop D provided with cross pieces, D' said hoop being attached at its upper side to the sleeve, C² and pivoted to the shaft, C' at the bottom of the kettle. To the upper end of said sleeve, C² is attached a miter gear c' and 90 the gear c² on the inner end of shaft, B², comes between the gears, c and c' and engages with both of them, so that when rotated, it imparts motion to the said gears, c and c' in opposite directions. The arms C and the 95 bars D' are made preferably triangular in cross section, and placed in the liquid so that one of their sharp edges shall come in front, so as to cut the liquid as it is moved forward in it. The bars, D', are connected at their 100 outer ends with hoop, D, and at their inner ends, to a collar or band, which is loose on the shaft, C'. This collar or band is also shown in connection with arms, C, where it has a set

screw by which it is fixed to said shaft, as seen in Fig. 3.

The sleeve, C², is journaled in the inner end of the frame, B', by means of a piece, B⁴, which is hinged at b' and has a slot in which a pivoted latch, b², on the supplemental frame works. Said pivoted latch has a thumb nut, b³, for clamping the part B⁴, upon the part, B', whereby said part, B⁴, is adapted to hold 10 the sleeve securely in place in its bearing, and at the same time, be readily detached by loosening the thumb nut, b³, sufficiently to allow the latch, b², to be turned out of said slot, so that the stirrers can be taken out of the kettle 15 with facility.

The stirrer, D, is provided with a series of scrapers, d, which are pivoted to eyes, d', secured to the scraper by means of pins, d², which are each provided with a coil spring 20 wound upon said pins and having a loop, d³, which is adapted to bear upon the scrapers and press them gently outward against the inner surface of the kettle: said scrapers are adapted to travel in different paths on the inner surface of the kettle, so that the several scrapers will cover the entire inner surface occupied by the materials to be mixed.

The kettle has a double bottom with space, E, between the two, which forms a steam chamber or receptacle for heating the kettle to reduce the material to be mixed by evaporation. This chamber communicates with steam pipes, E', which are set into the trunnions, a', as shown in Figs. 2 and 5, said trunnions being hollow, as shown at e, Fig. 5, so as to form a continuation of the pipe E', and the connecting pipes E², Fig. 5, which connect said pipes, E', through the hollow, e, with the source of steam supply, are fitted by steam-packed 35 joints, as shown in Fig. 5, so that said trunnions can revolve thereon; said joints being of ordinary construction and consisting of the packing, e' around the ends of pipes E², and the screw cap e², fitting upon the threaded 40 ends of the trunnions a'. One of the trunnions a', is provided with a handle, F, for tilting the kettle, said handle being attached to the trunnion by means of a collar, F', on one end of said handle, adapted to fit on the 45 trunnion and provided with a set screw, f, whereby it may be set or fixed rigidly thereto; said handle is attached to said collar by means of bolts, f' (Fig. 1) which pass through the flange on the end of the handle and through 50 a piece of wood, f², into said collar, said piece of wood being interposed for the purpose of insulating said flange and collar in order to prevent the handle from being heated by induction. The end of the frame, A', in which 55 the trunnions have bearing, is rounded and provided with notches, f³, (Figs. 1 and 5) and a handle is provided with a spring latch, f⁴, connected with a rod, F², which is connected with a lever handle, F³, pivoted to the handle F, so as to raise said latch against the pressure of the spring, out of the notches, f³, so that the kettle can be tilted or inclined, as

shown in Fig. 1, or still further over, so as to completely empty it of its contents and can be set and held by the latch, f⁴, in any of the 70 notches between the upright and inverted positions.

The supplemental frame, B' is provided with a projection or arm, G, which has a slot g, in its outer end, adapted to receive a pivoted latch, g', on the frame A', provided with a thumb nut whereby the supplemental frame B', can be secured or locked to the frame, A', when the kettle is in its upright or normal position; in which position, the wheel, B³, will 80 be thrown and held in gear with pinion, b, whereby the operating power is connected with the stirrers, and in this position, the stirrers may be set in motion by moving the handle, a³, in the direction required, to engage 85 the friction clutch, A³, with the operating pulley A⁴. I have adapted the clutch and pulley so that they will be engaged, and disengaged by slight movement of the clutch. This I do by mounting the pulley, A⁴, loosely 90 on the shaft, and limiting its movement longitudinally on said shaft by screw lock nuts, H, on the outer end of said shaft, and a collar, h, (Fig. 3) on the opposite side of said pulley, so that said pulley, while being free 95 to revolve on the shaft, has no longitudinal play thereon. The clutch and its yoke, H', are controlled by the screw rod, a², which is threaded in the projection, h', of the frame A'. The handle, a³, is fixed to said screw rod 100 so as to rock the same through a half revolution back and forth, thereby imparting a positive but slight endwise movement to said screw rod sufficient to engage and disengage the clutch and pulley.

In the bottom of the outer layer of the kettle, I provide an opening, i, (Fig. 3) through which one of the pipes, E', is connected with the steam chamber between the layers, and also provide a cock, i', in connection with said opening, whereby the water of condensation may be drawn off when necessary.

Having thus described my invention, what I claim, and desire to secure by Letters Patent, is—

1. In an apparatus for operating mixing kettles and in combination, a stationary frame provided with a driving shaft and pinion, a kettle pivoted in said stationary frame so as to tilt thereon, a supplemental frame mounted on said kettle, a revolving stirrer mounted on said supplemental frame and suspended in the kettle, and operating mechanism mounted on said supplemental frame connecting the revolving stirrer with the driving shaft and pinion mounted on said stationary frame; the supplemental frame and the parts mounted thereon moving with the kettle when tilted and throwing the operating mechanism out of gear with the driving pinion of the stationary frame, and into gear when the kettle is righted, substantially as specified.

2. The combination with the kettle pivoted to its supporting frame, of a supplemental

frame mounted on the kettle and tilting there-with, a stirrer journaled in said supplemental frame and suspended in the kettle, and operating mechanism mounted on said supplemental frame and adapted to operate the stirrer as specified.

3. The combination with the kettle pivoted to its supporting frame, of a supplemental frame mounted on the kettle and tilting there-with, an operating shaft, as B², journaled on said supplemental frame, two stirrers, as C C' and D D', suspended in the kettle from said supplemental frame and stationary mechanism adapted to be disconnected by the 15 tilting of the kettle and connected by the righting thereof with said operating shaft, B², for revolving said stirrers in opposite directions as specified.

4. The combination with the kettle, pivoted 20 to its supporting frame, of a supplemental

frame, mounted on the kettle, and a stirrer journaled in said supplemental frame by a bearing having one part hinged to the other, whereby the stirrer may be connected and disconnected with said supplemental frame, 25 as specified.

5. The combination with the kettle, of a revolving stirrer, as D, provided with hinged pressed scrapers, as d, adapted to scrape the interior of the kettle, as specified. 30

6. The combination with the kettle, pivoted to its supporting frame of the supplemental frame, mounted on the kettle and provided with an arm, G, and a latch g, on the supporting frame for locking said supporting and 35 supplemental frames together, as specified.
